UNITED STATES PATENT OFFICE.

JACOB HEINRICH LUDWIG BOETTCHER, OF ORANGE, NEW JERSEY.

MACHINE FOR PACKING ARTICLES.

Application filed June 4, 1923. Serial No. 643,355.

To all whom it may concern:

Be it known that I, JACOB HEINRICH LUDWIG BOETTCHER, a citizen of the United States, and resident of Orange, in the county 5 of Essex and State of New Jersey, have invented a new and useful Improvement in Machines for Packing Articles, of which the following is a specification.

This invention relates to a certain new 10 and original machine for facilitating the packing of crackers or other articles adapted to be packed thereby.

These articles are ordinarily stacked up and placed in the boxes by hand. This 15 results very often in more than the required number going into the box, which makes the box difficult to seal; and very often results in breaking some of the articles in the box.

20 An object of the invention is to provide such a machine which is of extreme simplicity, very cheap to manufacture, operable by unskilled labor, and which has very few parts which are at all likely to get out of order.

25 Another object consists in providing certain improvements in the form, construction and arrangement of the several parts, whereby the above named and other objects 30 may be effectively attained.

A practical embodiment of my invention is represented in the accompanying drawings, in which—

35 Fig. 1 represents a side view of the machine, the lower part of the supporting frame and driving belt being broken away.

40 Fig. 2 represents a cross sectional view taken in the plane of the line II—II of Fig. 1, looking in the direction of the arrows.

Figs. 3 and 4 represent longitudinal sectional views with parts broken away, illustrating the operation of the machine.

45 The machine includes an inclined trough or guideway designed to feed the articles to be packaged, together with a lever which resists the movement of the articles in the trough but which is so actuated as to intermittently permit a predetermined number of 50 the articles to pass downwardly, after which another mechanism comes into action and holds back the remainder of the body or column of the articles in the trough. The apparatus is arranged so that this predetermined 55 number of articles intermittently permitted to pass downwardly in the trough

may be varied so as to be just sufficient to fill the box or container into which the articles are to be packed. The lower end of the trough is provided with members 60 which are adapted to assist the operator in holding and spreading open the container and its liner, if any.

The reference numeral 1 designates the sloping trough or guideway, which has its 65 lower part 2 curved. The trough is supported on the standard 3, and, as illustrated, is composed of two angle-shaped members 4 and 5 united and spaced apart by braces and plates 6. A slot or opening is thus 70 provided along the centre of the trough for the passage of a member hereinafter described. The column of articles in the trough is indicated at *a* in Figs. 3 and 4.

Mounted on the standard 3 is a pulley 7 75 which is driven by a belt 8 which in turn may be driven by any suitable source of power, (not shown). This pulley is revolved at a comparatively slow speed and has on its outer face a crank pin 9 to which 80 is pivoted the crank 10. The other end of this crank is pivoted at 11 to a lever or stop 12 which is pivoted to the standard 3 at 13.

This lever 12 operates in the slot between 85 the two members 4, 5 and is designed to support the column of articles to be packaged and allow it to move down the trough when the mechanism (described later) has released the column.

90 Movable jaws operated through a lost motion mechanism constitute means whereby the column may be released and then stopped when a certain predetermined number of articles have advanced, and this means will now be described.

95 Pivoted at 14 to the lever 12 is a rod 15 which is supported at its free end in the bracket 16, secured to one of the plates 6. This rod 15 carries a sliding member 17 100 which cooperates with rollers 18 carried by a pair of jaws 19. These jaws are mounted at 20 on the standard 3 in such a manner as to permit them to be opened or closed. As illustrated in Fig. 2 a stud 21 105 carries the jaws, the jaws being mounted between a sleeve 22 on the stud and a spring 23. The holes in the jaws through which the stud passes are somewhat enlarged, thus allowing the jaws to be opened 110 to release the column of articles or closed, as in Fig. 2, to hold back the column.

Small blocks 24, having serrated faces, are secured to the jaws for actual engagement with the column of articles. These blocks 24 pass through opening 25 in the sides of the trough members 4, 5, and impinge against the edges of one or more of the articles at the front or lowermost point of the column.

Each jaw carries one of the rollers 18, previously mentioned. These rollers 18 are mounted on studs 26 carried by brackets 27, which are secured to the jaws. A spring 28 fastened to the studs 26 tends to pull the jaws together and hold them in closed position.

When the sliding member 17 comes in contact with rollers 18 it spreads the jaws apart, allowing the column of articles to move down as fast as the pivoted lever 12 will permit. The end of the sliding member 17 is rounded or tapered at 29 so as to enable it to enter more readily between the rollers 18, and the member is made of smaller diameter at its intermediate part 30 so that the rollers 18 may hold it more firmly until it is desired to disengage it from the bite of the rollers and allow the jaws to close.

A stop 31 for the sliding member 17 is threaded on the rod 15. When the machine is in the position shown in Fig. 1 and the jaws are holding the column of articles, the sliding member is against this stop 31. As the lever 12 moves upwardly to engage and hold the column of crackers, as in Fig. 3, this stop forces the member 17 between the rollers 18 and holds the jaws 19 open while the column of articles is permitted to descend in the guideway. The rod 15 is then sliding through the member 17.

When the certain predetermined number of articles has been allowed to advance, a stop 32 engages the member 17 and forces it out of the bite of the rollers, whereupon the jaws 19 close and the blocks 24 stop the column from moving any further. By changing the distance between these stops 31 and 32 the number of articles allowed to advance will be varied, so that the number of articles to be advanced may be accurately predetermined and will always be absolutely the same unless intentionally changed by adjusting the stops 31 and 32. These stops 31 and 32 are illustrated as nuts mounted on threaded portions of the rod 15, but they may be constructed in any way so as to obtain the desired adjustability.

Means is provided to hold the articles erect after they have come to the lower curved part of the trough and before the operator puts them in the box. This means comprises a pair of light, flexible spring members 33 secured to the sides of the trough. These members are so light and flexible that there will be no tendency for them to break the articles or seriously

impede the movement of the articles when the operator is pushing them past these spring members, but yet they are sufficiently strong to prevent the articles from falling flat, which would be very undesirable.

Means is provided on the end of the trough to assist in holding the box or container and spreading it open, and this will now be described. The boxes or containers in which the articles are placed are frequently lined with an air tight paper. To keep this paper spread open so as not to interfere with the entrance of the articles into the box is an important result which this machine accomplishes in a very simple way.

A flat, fixed member 34 is secured at the lower end of the trough, and a pair of light, flexible members 35 are secured on arms 36 which are pivoted at 37 to the trough. The open end of the box and its lining are placed over these members just described and held in position by the operator. When these members are collapsed or closed, as shown in Fig. 1, the box may readily be placed over them and, as the operator pushes the articles into the box, the articles themselves open the members 35 so that the container is not only spread open but a guide is formed for the articles entering the container. Another pair of light, flexible spring members 38 materially assist in forming side guides and keep the lining at the sides of the container from interfering with the articles entering the same.

A brief description of the operation follows. The guideway or trough is kept full of articles by the operator. The belt 8 drives the pulley 7 which, through the medium of the crank pin and crank 9 and 10, moves the pivoted lever 12. In the position shown in Fig. 1 a predetermined number of articles will be supported in the flexible members 33 and the operator will be ready to place the box or container in position and push the articles thereinto.

The lever 12 will then move to the position shown in Fig. 3. The member 17 will separate the jaws and the column of articles will be held or supported by the lever 12. The lever 12 then starts to move back toward the position in Figs. 1 and 4, allowing the column of articles to move in the guideway. When the stop 32 engages the member 17, just prior to the position shown in Fig. 4, the member 17 is removed from the bite of the rollers 18 and the jaws close, stopping the column. The certain predetermined number of articles designated a^1 are then permitted to advance down the trough.

When the lever 12 moves out of their path the articles a^1 descend and are held in their proper position by the flexible members 33. The operator then places a container on the end of the trough over

the members 34, 35 and 38 and, with an implement of any desired shape, pushes the articles into the box. This procedure is repeated as long as the machine continues in 5 operation. The machine may be started and stopped as desired by any suitable form of clutch (not shown).

I desire it to be understood that various 10 changes may be resorted to in the form, construction and arrangement of the several parts without departing from the spirit and scope of my invention; hence, I do not intend to be limited to the details herein shown and described except as they may 15 be included in the claims.

What I claim is:

1. A machine of the character described comprising, a guideway for feeding a column of the articles, a movable stop for 20 restraining the feeding movement of the articles, means for intermittently moving the stop out of engagement with the articles in order to permit the passage of a predetermined number thereof, and a pair of 25 jaws for restraining the feeding movement of the articles after the passage of the said predetermined number, said jaws comprising elements located on opposite sides of and extending into the said guideway.

2. A machine of the character described

comprising, a guideway for feeding a column of the articles, a movable stop for restraining the feeding movement of the articles, means for intermittently moving the stop out of engagement with the articles 35 in order to permit the passage of a predetermined number thereof, a pair of jaws for restraining the feeding movement of the articles after the passage of the said predetermined number, and mechanism carried by the stop moving means for controlling the action of the jaws.

3. A machine of the character described comprising, a guideway for feeding a column of the articles, a movable stop for restraining the feeding movement of the articles, means for intermittently moving the stop out of engagement with the articles 40 in order to permit the passage of a predetermined number thereof, a pair of jaws 45 for restraining the feeding movement of the articles after the passage of the said predetermined number, and adjustable mechanism carried by the stop moving means for controlling the action of the jaws.

In testimony, that I claim the foregoing as my invention, I have signed my name this 31st day of May, 1923.

JACOB HEINRICH LUDWIG BOETTCHER.
